UNITED STATES PATENT OFFICE.

WILLIAM E. WINE, OF TOLEDO, OHIO.

CAR-DOOR LOCK.

Application filed February 17, 1921. Serial No. 445,745.

This invention relates to door mechanism for railway cars or the like and the principal object thereof is to provide a simple and convenient means for holding such doors in closed position.

Another object is to provide an improved arrangement of locking member or hook adapted to supportingly engage a portion of the door and to provide for use with a door-supporting hook an improved hook bracket or housing, also improved means attached to the door for engagement by the hook. A still further object is to provide a door-supporting arrangement that will be of low cost and applicable to the car as a simple self-contained and pre-assembled unit of car construction.

With these and other incidental objects in view, the invention consists of the formation, combination and arrangement of parts as will be herein described and finally claimed.

In the accompanying drawings, which show an embodiment of the invention, Figure 1 is a side elevational view of the mechanism of the present invention, along with sufficient of the adjacent car construction as to illustrate its co-operation therewith. In this figure certain portions of the locking mechanism are shown in section for the purpose of clarity. Figure 2 is a vertical cross sectional view taken through a portion of the car structure, substantially on the line 2—2 of Figure 1, and showing the door locking device in end elevational view. Figure 3 is a plan view of the mechanism and the adjacent portion of the car, and Figure 4 a horizontal cross sectional view taken on the line 4—4 of Figure 1.

Referring now to these drawings, that portion of the side of the car shown is designated 1 and the floor 2. A pair of doors 3 and 4 are provided for the car in its floor, the door 3 being shown complete in Figure 1 but the hinge portion of the door 4 being broken away. These doors are hinged to the car structure along their remote edges as shown at 5 for the door 3. It will be understood that similar hinges are used for the door 4 also. The free edges 7 and 8 of the doors are turned toward each other. Angle irons 9 and 10 are furnished for the free edges of the doors. These may extend for the full length of the doors and are supplied to stiffen and support the same. The ends 55 of these angles extend outward beyond the

sides of the car and the projecting ends cooperate with the later described locking mechanism to hold the doors in closed positions. Brackets 11, of triangular form, extend across and within the openings of 60 the angles 9 and 10 to stiffen the ends of the same in the vicinity of the locking mechanism. These brackets or braces are riveted to the inner faces of the two legs of the angle by means of the rivets 12, thereby 65 securely bracing and tying the two legs together and making a stiff construction for a locking face.

By arranging for the supporting ledges 23 of the latches to seat beneath the lower edges 70 of the outstanding legs of the angle irons to support the door, the metal of the angle irons is presented in an advantageous manner and the doors will not spring down from the local yield of the angles. And by locally stiffening these outstanding legs near 75 their lower edges, as for example by the brackets 11, the angle irons are prevented from distorting from the concentration of loads.

The present mechanism does not include 80 any special apparatus for lifting the doors, it having been found satisfactory to lift them up by hand, grasping the protruding ends of the angle irons 9 and 10. The invention has primarily to do with an effective device whereby, when the doors are raised they will latch themselves and will be held in closed position in a simple and positive manner, and also so that they may 85 be readily released.

To this end, a bracket 13 is riveted to the outer face of the car side in a position adjacent to the free edges of the two doors 3 and 4 which constitute a pair. Several 90 of the regular bottom flange rivets 14 may be utilized for the attachment of this bracket, this series of rivets being supplied normally for securing the flange bar 15 to the car side 1. Latches or hooks 16 and 17 are 95 pivoted to the bracket 13 at 18 and 19, these serving to hold the doors 3 and 4 respectively in closed positions. The integral bracket 13 has front and rear walls 20 and 21, the space 22 between the walls forming 100 a pocket for the said latches.

The rear or inner wall 21 constitutes the base of the bracket and the front or outer wall 20 constitutes a guard to overlie the major portion of the hooks or latches 16 110

and 17, the guard extending over the upper ends and the shanks thereof as well as portions of the latching shoulders of the same. The bracket 13 being thus securely and permanently attached to the car, it becomes in effect an extension from the car side.

The doors are preferably arranged in planes approximately coincident with the plane of the bottom edge of the car side so as to utilize the edges of the sides as hopper openings. The bracket 13 is accordingly extended downwardly for some distance below the side of the car in order that the latches may be pivoted thereupon at the desired locations with respect to the plane of the doors. This form of bracket is especially adapted for use with cars of the type illustrated in the drawings. It is also contemplated to apply the invention to cars of other types, hence limited modifications within the scope of the appended claims, may be necessary.

The latches 16 and 17 have locking shoulders at their forward edges and there fit under the upright legs of the angles 10 and 9, the lower edges of the said legs of the angles thus constituting locking faces for and upon the doors. The engagement points between the latches and the doors fall outside of the pivot points 18 and 19, or between the pivot points of the latches and the door hinge points, as for example, the engagement point for the door 3 lies between the pivot point 18 and the hinge point 5. This contact point also lies above the latch pivot point 18, or between the pivot point 18 and the door itself, when the latter is in closed position as shown. The latch 16 is in position, when swung back toward the other latch 17, to entirely clear the path of the angle iron 10 and to allow the door to drop, the angle iron being the limit of, or the free edge of the door, in the vicinity of the latch. When the door is lifted short the inclined face 24 of the latch will cause the same to be pushed clear of the door and the latch will then fall by gravity, or it may be swung into engagement beneath the angle iron, and as the weight of the door comes upon it the tendency will be for the latch to be swung toward the angle iron, or into further engagement with the door. This is due to the relative location of the parts. End walls, such as at 25, are provided for the pocket of the casting 13 to limit the outward movement of the latches or hooks 16 and 17.

The pivot pins for the latches pass through the inner and outer walls of the bracket but not through the car side, so that the latches are in reality pivoted upon the bracket. But as the bracket with its contained parts is applicable to the car as a unit, the latches are in effect pivoted to the car body.

It is one of the objects of the invention to provide a device so constructed that it may be readily applied to and removed from the car after pre-assembling of the several parts within the bracket. To this end any convenient arrangement of attachment of the bracket to the car may be employed. In the present embodiment the upper portion only of the inner wall or base 21 of the bracket 13 lies against the side 1 of the car, the outer wall 20 of the bracket, together with the upright end walls 25 forming with the base 21, a housing to accommodate the hooks 16 and 17 which are operably accommodated therein. The housing is open at the bottom so that the latches may be entered and these are then pivoted upon and between the base portion 21 of the casting and the outer wall 20 by means of the pivot pins located at the pivot points 18 and 19. As before stated, these pins are in the present embodiment arranged near the lowermost edge of the housing, and below the lowermost edge of the car side, although other locations might be found to be desirable in other embodiments. To the end that the device may be preassembled and applied to the car body as a single unit of construction, it is desirable, as shown in the drawings, that the pivot pins should pass through the integral walls 20 and 21 but not through the side of the car, as otherwise it would be difficult, or even impossible to fit together and assemble the latches, lock and bracket remote from the car and then apply the complete outfit to the car as a separable self-contained unit. It is desirable from the standpoint of strength and stiffness that the pivot pins pass through both the inner and outer walls of the bracket, and in order to effect economy and ease of application it is preferable that the rivets such as 14 for securing the outfit to the car body shall pass through the base 21 of the casting only, as it is then not necessary to extend the outer wall 20 over the full face of the inner wall or base 21, but it may be made of just sufficient extent to properly house and support the hooks and form a guard therefor.

The end walls 25 which are integral with and connect the inner wall or base 21 and the outer wall 20, extend along the forward edges of the hooks 16 and 17 and are shaped to substantially conform to these edges, so that these end walls define the forward limits of the housing and also form stops for limiting the forward movement of the hooks, or in other words serve to limit movement of the hooks toward their respective doors. These walls 25 are preferably extended to follow around the contour of the tops of the hooks, thus following angular paths whereby is provided stiffness for the bracket without excessive weight or cost, as the angular disposition of the upper portions of the

walls 25 will effectively tie the outer wall 21 to the inner wall or base portion 20 of the casting, affording stiffness and rigidity in all directions.

It will be noted that the weight upon the latches will cause them to approach the doors, until arrested by contact with the walls 25. Also that upon release, either of the two latches must be moved toward the other one. In order to hold the latches against possible disengagement with the locking faces of the doors, or in other words, in order to hold them forwardly in the housing and substantially against the end walls 25, latch lock 26 is provided, the same to be dropped into position between the latches 16 and 17 so that neither of these latches can be swung back without first withdrawing the lock 26. While it is contemplated that the latches will, as a rule, gravitate into door engaging and supporting position, it will be appreciated that they may in some instances after having been in service a long time be prevented from doing so by excessive friction between the parts, by improper adjustment of the parts due to accidental distortion or by an accumulation of dirt, snow or ice in the bracket. To obviate this difficulty and thereby insure complete locking rotation of the latches, the lower part of the slidable lock 26 is formed as a symmetrical wedge adapted to cooperate simultaneously with the upwardly projecting portions of the latches to force them toward their respective door supporting positions. This lock fits in the pocket 22 of the casting 13, and guides or ribs 27 are provided to form a way for its operation. The integral ribs or walls 27 also serve to connect the spaced walls 20 and 21 of the bracket and, together with the walls 25, complete therewith the pocket for the operable accommodation of the latches 16 and 17 and the locking block 26. As this lock fits between the latches 16 and 17 it will be seen that tendency of either latch to move out of engagement with its door will cause the opposite latch to be forced into still further engagement with its door unless already in full engagement therewith. When the lock is lifted up either latch may be swung from beneath its door with a consequent dropping of the door. The lock has a lip 28 which may be used for driving the lock upwardly for disengaging the latches or, if the latches fail to rotate completely into door supporting position, it may be used for driving the lock downwardly for forcing the latches into that position.

It will be noted that the stop walls 25 for limiting the movement of the latches into engagement with the doors, as well as the point of engagement of the locking block 26 with the latches 16 and 17, is above the level of the locking shoulders 23 of the

latches, the stop walls engaging the latches on the outer sides thereof, or on the sides of the latches toward the respective doors and the stop block engaging the latches on the inner sides, or in other words, upon the sides away from their respective doors. This arrangement provides a maximum leverage for the effect of the stop wall and locking block upon the latches, which in the present construction may be made unusually small and of relatively light weight.

The present arrangement permits the entire bracket, with the latches and locking block in place, to be assembled as a complete operable unit before being applied to the car and be then applied in a proper position to match with the doors, irrespective of whether the latter have been carefully manufactured and applied to the car or not. This is of great convenience in this art, as the car builder usually prefers to avoid all exactness in manufacture, except where absolutely necessary. It is the plan in the practical application of this invention that the assembled bracket outfit will be turned out in a separate shop employing labor of the necessary skill to fit up the parts with such nicety as may be necessary and the assembled unit will then be applied to the car by the regular workman in a proper position to take care of any ordinary irregularities in the construction or application of the doors.

Thus has been described a preferred embodiment of the invention.

What is claimed is:

1. A door mechanism for railway cars including a swinging door hinged along one of its edges to the car structure, a pivoted latch for holding the door in closed position the same having a locking face for engagement with a portion of the door, the locking face being located above and to one side of the pivot point of the latch, and a lock-retaining member cooperable with the said latch and arranged to engage the same at a point above the said locking face thereof.

2. A door mechanism for railway cars including a swinging door hinged along one of its edges to the car structure, a pivoted latch for holding the door in closed position the same having a locking face for engagement with a portion of the door, the locking face being located above the pivot point and to the side thereof adjacent the hinged edge of the door, and a lock-retaining member cooperable with the said latch and arranged to engage the same at a point above the said locking face thereof and at the side thereof away from the hinged edge of the door.

3. A door mechanism for railway cars including a swinging door hinged along one of its edges to the car structure, the plane of the door being approximately coincident with the plane of the lower edge of the car

- side, a bracket attached to the car side and depending below the lower edge thereof and below the plane of the door, a latch pivoted upon the bracket at a point beneath the door 5 and slightly removed from the free edge of the same, the latch having a locking shoulder adapted to seat beneath a portion of the door when the latter is in closed position.
4. A door mechanism for railway cars including a door hinged along one of its edges to the car structure, and having a locking face near another edge, a latch pivoted to the car structure beneath and outside the limits of the door, the said latch having a 10 locking shoulder extending outwardly therefrom toward the door and located between the said pivot point and the locking face on the car door, the said latch being arranged in such manner that it may be swung entirely out of the path of traverse of the door and being further arranged that it may be swung toward the door a sufficient distance to permit the said locking shoulder to seat beneath the locking face when the door is 15 closed, and lock-retaining means arranged to engage the latch at the side thereof away from the door and at a point above the locking shoulder.
5. A door mechanism for railway cars including a door hinged along one of its edges to the car structure, a latch pivoted to the car structure beneath and outside of the limits of the door, the said latch having a shoulder arranged to extend inwardly beneath the door to support the same in closed position, the pivot point of the latch being so arranged with respect to the shoulder that the weight of the door will tend to rotate the latch toward the door, and there being 20 means coacting between the latch and the car structure for limiting such rotation, said limiting means being arranged to engage the latch above the said shoulder thereof.
6. A door mechanism for railway cars including a door hinged along one of its edges to the car structure, a latch pivoted to the car structure beneath and outside of the limits of the door, a locking shoulder extending outwardly from the latch, the same being so arranged that upon rotation of the latch it may be positioned beneath the door in proper manner to support the same in closed position or entirely withdrawn from beneath the door, the pivot point of the 25 latch being so arranged with respect to the shoulder that the weight of the door will tend to rotate the latch into further engagement with the door, there being means coacting between the latch and the car structure for limiting such outward rotation and there being removable means for preventing inward rotation of the latch, the said means for limiting the outward rotation of the latch and the said means for preventing inward rotation thereof both being arranged 30 to engage the latch above the shoulder thereof.
7. A door mechanism for railway cars provided with a pair of doors hinged to the car structure, said mechanism including a plurality of relatively movable door locking members each adapted to engage one of the doors, and movable means interposed between said members for normally retaining them in door locking relation, said means and said locking members being so related that when in locked position a tendency of one locking member to accidentally assume unlocked position will transmit through said means force tending to effect a locking 35 movement of the other locking member.
8. A door mechanism for railway cars including a pair of doors hinged to the car structure, a latch for each door adapted to be swung into the path of travel of the door in such manner as to hold the same in closed position, and movable means acting between the latches whereby motion of one latch to release its door will produce a reverse movement of the other latch.
9. In a door mechanism for railway cars, a pair of doors hinged to the car structure, a bracket affixed to the car structure between adjacent free edges of the doors, a supporting latch for each door, the same being pivoted upon the bracket, and a latch-interlocking member operatively mounted upon the bracket and arranged to hold the latches in engagement with their respective doors, the latches being independently disengagable with their respective doors upon the withdrawal of the said interlocking member.
10. A door mechanism for railway cars including, in combination with the car body, a door hinged thereto, a latch for the said door and a lock for the latch, and a casting attached to the car body, the same having integral outer and inner walls spaced from each other, integral ribs connecting said walls, the said latch and lock being positioned between the said walls.
11. A door mechanism for railway cars including in combination with the car body, a door hinged thereto, a latch for the said door and a lock slidably mounted for engagement with the latch to maintain the latter in door supporting position, and a casting attached to the car body, the same having a pocket formed by integral spaced walls, the said pocket being formed to receive and operably accommodate the said latch and lock.
12. In a door mechanism for railway cars, a pair of doors hinged to the car body, each door being provided with a locking face, a pair of latches pivoted to the car body and arranged to be swung into engagement with the locking faces of the doors, and a locking block slidably interposed between the latches, the same being movable into or out 125 of the latches.

of a position where the said latches are held thereby in positive engagement with the locking faces of the doors.

13. In a door mechanism for railway cars, a pair of doors hinged to the car body, each door being provided with a locking face, independent door-supporting latches operably associated between the car body and the locking faces of each of the doors, and a single locking block arranged to be moved into or out of locking engagement with both latches.

14. In a door mechanism for railway cars, a pair of doors hinged to the car body, a supporting latch for each door, the same being located upon the car near the free edge of the respective doors, the said latches being arranged to move toward each other to release the respective doors, and a locking block removably interposed between the latches and arranged to prevent releasing movement thereof.

15. In a door mechanism for railway cars, a pair of doors hinged to the car body, a supporting latch for each door, the same being pivoted to the car near the free edges of the doors and arranged to swing towards each other for the release of the respective doors, and a locking block slidably interposed between the latches and arranged to prevent releasing movement thereof.

16. In a door arrangement for railway cars, a pair of doors hinged to the car body along their remote edges and arranged to swing toward each other into closed positions, a door locking mechanism for the said doors, the same being formed as a single self-contained unit attachable to the car independently of any other part and including a bracket, independent locks upon the bracket for each door, and additional means upon the bracket for holding the said locks in position.

17. A door mechanism for railway cars including, in combination with the car body, a door hinged thereto, a supporting latch for the said door, the same being pivoted upon the car body, an angle iron extension secured to the door and extending outwardly therefrom, one leg of the angle lying against the door plate and the other leg outstanding from the door plate, the said latch being arranged to supportingly engage and seat beneath the outer edge of the said outstanding leg, the portion of the latch above the supporting ledge thereof lying parallel with the back of the said outstanding leg.

18. A door device for railway cars including in combination with the car body a door hinged thereto, a bracket having integral inner and outer spaced walls, the inner wall lying against a wall of the car and being secured thereto, a door-supporting latch disposed between the said walls of the bracket and pivoted thereupon, the pivot pin there-

for passing through both of said walls of the bracket, but not through the said wall of the car that is adjacent the inner wall of the bracket.

19. In a dump car having a pivoted door, the combination with a bracket secured to a fixed part of the car adjacent an edge of the door when the latter is in closed position, of a bar rigid with the door and projecting from said edge in line with said bracket, a locking lever pivotally supported on said bracket to swing against said bar on the under side of the latter, and means for holding said lever in locked position.

20. In a dump car having a pivoted door, the combination with a bracket secured to a fixed part of the car adjacent an edge of the door when the latter is in closed position, of a bar rigid with the door and projecting from said edge in line with said bracket, and a locking lever pivotally supported on said bracket to swing against said bar on the under side of the latter, said bracket having a supporting ledge on which the free end of said lever rests when in locked position.

21. In a dump car having a pivoted door with the free edge thereof adapted to swing downwardly when opening, the combination with a bracket secured to a fixed part of the car and having a portion extending across the side edge of the door when the latter is in closed position, of a projection rigid with the door and extending from said side thereof, a lock lever pivoted to said portion of the bracket adapted to swing to a position on the under side of said projection, said bracket having a supporting ledge for the free end of the lever.

22. In a dump car, the combination with a pair of pivoted doors adapted to swing oppositely and having their free edges meeting when in closed position, of a bracket secured to a fixed part of the car opposite the line of meeting of said free edges of the doors, a projection rigid with each door, and a pair of independently operable locking elements supported from said bracket and cooperable with the respective door projections to lock the doors in closed position.

23. In a dump car, a discharge door, a bracket secured to said car, a member pivotally mounted in said bracket and adapted to support said door in closed position, and an extension on said member adapted to engage said bracket when said member is in door supporting position.

24. In a dump car, a discharge door, a bracket secured to said car having spaced front and rear portions, a member pivotally mounted between said portions, adapted to support said door, an extension on said member, adapted to engage said bracket between said portions, and a locking member adapted to engage said extension.

25. A door supporting device for railway car door mechanism, said device including a plurality of pivoted door supporting latches, the door engaging portions of said latches being adapted to swing upwardly and toward each other when executing an unlocking movement, and movable means operatively interposed between and adapted simultaneously to cooperate with said latches to maintain the latter in door supporting relation. 10
26. A door supporting device for railway car door mechanism, said device including a plurality of pivoted door supporting latches adapted to swing toward each other when executing a door releasing movement, and means operable independently of said latches to simultaneously force the latter toward their respective door supporting positions. 15
27. A door supporting device for railway car door mechanism, said device including a plurality of pivoted latches adapted to swing in opposite directions to door supporting position, and means interposed between and operable independently of said latches to simultaneously cooperate with the latter for forcing them toward their respective door supporting positions. 20
28. A door supporting device for railway car door mechanism, said device including a plurality of pivoted door supporting latches adapted to swing toward each other when executing a door releasing movement, and means movable independently of said latches for preventing door releasing movement of the latter, said means extending between and engaging said latches. 25
29. A door supporting device for railway car door mechanism, said device including a plurality of independently movable door supporting latches adapted to move in opposite directions, and means cooperating with said latches to cause them simultaneously to move in opposite directions. 30
30. A railway car having a lading discharge opening, a door for closing said opening, door locking mechanism carried by the car involving a bracket and a slidable locking member, said bracket having a passageway within which the locking member is adapted to move, and movable means operatively interposed between the door and locking member for engagement with the latter to support the door in closed position. 35
31. A railway car having a lading discharge opening, a door for closing said opening, door locking mechanism carried by the car involving a bracket and a slidable locking block, the said bracket being formed with integral portions forming a passageway within which the locking block is adapted to move, the lower portion of said block being provided with a wedging face, and pivoted means operatively interposed be- 40
- tween the door and locking block for engagement with the latter to support the door in closed position. 45
32. A railway car having a lading discharge opening, a door for closing said opening, and means for maintaining the door in closed position, said means involving a pivoted member, a slidable member engageable with said pivoted member, and a bracket having a passageway within which the slidable member is adapted to move, the latter having an offset portion affording means to which force may be applied for moving the same. 50
33. A railway car having a lading discharge opening, a door for closing said opening, said door having a beam extending outwardly beyond one of its edges, the outwardly extending portion of said beam being provided with a reinforcing bracket, and a movable member cooperable with the beam for maintaining the door in closed position, the said bracket being fashioned with a stiffening web disposed in a plane substantially parallel to the plane of operation of the said movable member. 55
34. A railway car having a lading discharge opening, a door for closing said opening, a member secured to the door, having angularly disposed plate-like portions, one of said portions extending outwardly beyond the edge of the door and substantially normal to the plane of the door, and a movable door supporting hook carried by the car body for maintaining the door in closed position, the said hook being adapted to seat beneath the outer edge of the outwardly extending plate-like portion of the said member, and being so arranged that the weight of the door acting thereon will tend to cause it to execute a further locking movement. 60
35. In a railway car having a lading discharge opening, the combination with a door for closing said opening adapted to move to open position under the influence of gravity, of mechanism for supporting the door in closed position involving pivoted means operatively interposed between the door and car body, a slidable locking member engageable with said means, and a bracket secured to the car body having a passageway within which said locking member is adapted to move. 65
36. In a railway car having a lading discharge opening, the combination with a door for closing said opening adapted to move to open position under the influence of gravity, of mechanism for supporting the door in closed position involving pivoted means operatively interposed between the door and car body, a slidable locking member movable into and out of engagement with said means, and a bracket secured to the car body having a passageway within which said locking 70

member is adapted to move, the upper end of the latter being fashioned with a laterally projecting portion affording means to which force may be applied for moving the same.

- 5 37. In a railway car having a lading discharge opening, the combination with a door for closing said opening adapted to move to open position under the influence of gravity, of mechanism for supporting the door in closed position involving pivoted means operatively interposed between the door and car body, a bracket secured to the car body, and a gibbed locking member slidably mounted on said bracket for engagement with said pivoted means, the locking member being provided with a laterally offset portion affording means to which force may be applied for moving the locking member into and out of engagement with the pivoted 10 means.
- 15 38. In a railway car having a lading discharge opening, the combination with a hinged door for closing said opening, said door being movable to open position under the influence of gravity and having its hinge 20 axis disposed transversely of the car, of mechanism for supporting the door in closed position involving movable means opera-

tively interposed between the door and car body and operating in a plane spaced outwardly from the adjacent portion of the said body, a bracket secured to the latter and projecting outwardly therefrom, and a locking block slidably mounted in said bracket for engagement with the said movable means, the said block being fashioned with a tapered lower portion and a lipped upper portion.

- 30 39. In a railway car having a lading discharge opening, the combination with a hinged door for closing said opening adapted to swing to open position under the influence of gravity, the hinge axis of said door extending transversely of the car, of mechanism for supporting said door in closed position involving a bracket secured to the car body and projecting outwardly therefrom, a locking block slidably mounted in said bracket, and movable means operatively interposed between the door and car body, the said locking block being movable into the path of operation of said means for restraining movement thereof.

In testimony whereof I affix my signature.

WILLIAM E. WINE.
